UNITED STATES PATENT OFFICE.

LOUIS C. LOEWENSTEIN, OF LYNN, AND HARVEY N. DAVIS, OF CAMBRIDGE, MASSACHUSETTS, ASSIGNORS TO GENERAL ELECTRIC COMPANY, A CORPORATION OF NEW YORK.

BOILER.

Application filed October 28, 1919. Serial No. 333,996.

To all whom it may concern:

Be it known that we, LOUIS C. LOEWENSTEIN, a citizen of the United States, residing at Lynn, county of Essex, State of Massachusetts, and HARVEY N. DAVIS, a citizen of the United States, residing at Cambridge, county of Middlesex, State of Massachusetts, have invented certain new and useful Improvements in Boilers, of which the following is a specification.

The present invention relates to boilers, especially to those intended for vaporizing fluid having a high boiling point with respect to water and more especially to heavy fluids, such as mercury for example.

The object of our invention is to provide an improved construction and arrangement in a boiler of this character; and, for a consideration of what we believe to be novel and our invention, attention is directed to the accompanying description and the claims appended thereto.

In the drawing, Fig. 1 is a front elevation of a boiler embodying our invention, walls at certain points being broken away to better illustrate the structure; Fig. 2 is a side view of a part of the boiler; Fig. 3 is a top plan view on a larger scale than Fig. 1 of a part of the boiler, part of a top wall being broken away; Fig. 4 is a section taken on line 4—4, Fig. 1; Fig. 5 is a section taken on line 5—5, Fig. 1; Fig. 6 is a section taken on line 6—6, Fig. 1; Fig. 7 is a section taken on line 7—7, Fig. 1; Fig. 8 is a section taken on line 8—8, Fig. 1; Fig. 9 is a section taken on line 9—9, Fig. 1; and Fig. 10 is a section taken on line 10—10, Fig. 1.

One particular application of our mercury boiler is in connection with a power generating system in which mercury vapor is used to drive a turbine or other prime mover, and the exhaust mercury vapor therefrom employed to generate steam from water which in turn is supplied to a turbine or other prime mover preferably of the condensing type, said turbines driving electric generators or other apparatus. Hereinafter for convenience the boiler will be particularly described as a mercury boiler but it will of course be understood that it is not limited necessarily to use with mercury.

Referring to the drawing, the boiler comprises a plurality of grids or cells 15 which

are suitably supported in spaced relation to each other in an enclosing casing and between which the flue gases pass. The grids are all alike and each comprises two thin sheets of metal 16 and 17 slightly separated to form a liquid space and a vapor space between them. The sheets are sealed or fastened together around their edges, as by welding them together, except where the liquid enters and the vapors are discharged; and they are supported in spaced relation to each other by providing a plurality of projections on one or both sheets and spot welding them as indicated at 18. The spot welds may be distributed as found desirable to give the necessary strength and rigidity. In order to direct the circulation of mercury and mercury vapor between the sheets of each grid, partitions as indicated at 19 and 20 (see Fig. 1) are provided which cause the mercury and mercury vapors to follow a path as indicated by the dotted arrows in Fig. 1. As arranged, the liquid mercury enters the grid at each of its lower corners and is caused to flow along the bottom of the grid beneath the horizontal parts of partitions 19; and, as vapor is formed, it flows upward at the center of the grid until it meets the horizontal parts of partitions 20. The vapor is then directed downward and flows under the bottom edges of partition 20 and thence upward again to the point of escape. Along each vertical edge of the grid is a mercury passage 21 formed by making a corrugation or cone shaped groove 22 along each edge of one sheet, as the sheet 17, and welding the edge of the other sheet 16 over the open side of these corrugations. This is best shown in Figs. 4, 5 and 9. At their lower ends passages 21 communicate with the space between sheets 17 and 16 as shown in Fig. 9, this being beneath the horizontal portion of partition 19. The upper ends of passages 21 connect with headers 23 which extend along the two sides of the boiler at the top thereof. At its upper end the grid connects to a tube sheet 24 which forms the bottom wall of a vapor header 25. A part of tube sheet 24 is shown in plan in Fig. 3, the slots in it through which vapor enters from the cells being indicated at 24a. From vapor header 25 a conduit 26 leads to a

mercury turbine or other prime mover and serves to convey vapor from the header to the turbine.

The boiler comprises a number of grids or cells as just described, placed side by side and supported at their upper corners by rods 27, the grids being provided with ears 28, having openings through which rods 27 pass. On rods 27 between ears 28 are spacing sleeves 29 (Fig. 3) for holding the grids in spaced relation to each other. The bottoms of the grids are supported on a plate 30 having a central opening 31 through which the flue gases enter between the grids. The fire box of the boiler is not shown but it may be of any suitable arrangement and is located beneath plate 30 so that the hot products of combustion may pass from the fire box up between the grids. At the top 20 of the grids at each side of vapor header 25 the spaces between the grids are closed by suitable flanges 32 (Fig. 3) and by a covering of heat insulating material 33.

The general construction of grid and boiler so far described is more particularly described and is claimed in our co-pending application Serial No. 284,383, filed March 22, 1919, and patented April 14, 1925, Patent No. 1,533,706.

Now in a boiler of this type it is clear that only a small amount of liquid is contained in the grids at a time and if successful operation is to be obtained there must be rapid circulation of such liquid to carry away heat from the flue gases and also rapid circulation and good distribution of the flue gases to heat as evenly as possible the entire surfaces of the grids. Particularly it is important that there be no pockets where flue gases can stagnate.

More particularly the object of our present invention is to provide an improved structure and arrangement which will insure a rapid circulation and even distribution of the flue gases, and to this end we provide each grid with corrugations so arranged that a number of passages preferably diamond-shaped in cross section are provided. The passages are formed by placing the corrugated grids together in such manner that the edges of the corrugations engage each other, as is obvious from an inspection of the drawing. The corrugations are also preferably so arranged that the flue gases flow upward at the central portion of the boiler; thence laterally across the top of the sides thereof and then down again at the sides and out. From an inspection of Fig. 1 it will be seen that as regards the flow of flue gases this arrangement in substance divides the boiler into right hand and left hand sides. The flue gases entering the boiler through opening 31 flow upward through vertical passages 35 (Figs. 1, 4, 5 and 6) then laterally through passages 36

(Figs. 1 and 8) and then down through passages 37 (Figs. 1 and 4) to the bottom of the boiler. At the bottom of the boiler passages 37 turn laterally as indicated at 38 (Figs. 1 and 5) and the flue gases pass out through openings 39 formed between cone-shaped grooves 22 (Figs. 1, 2 and 5).

It will thus be seen that we provide definite paths for the flue gases and that they will be drawn through these paths without danger of gas pockets or points of inactive flow being established.

The mercury or other fluid to be vaporized flows from headers 23 down through passages 21, which form in substance pre-heaters for the mercury, to enter the grids at the bottoms through the passages as best shown in Fig. 9 and then follows the course already described and indicated by the dotted arrows arriving at header 25 in the form of superheated vapor.

In accordance with the provisions of the patent statutes, we have described the principle of operation of our invention, together with the apparatus which we now consider to represent the best embodiment thereof, but we desire to have it understood that the apparatus shown is only illustrative and that the invention may be carried out by other means.

What I claim as new and desire to secure by Letters Patent of the United States, is:—

1. A boiler comprising a plurality of spaced grids each comprising two thin metal sheets united along their edges, partition means between the sheets of each grid for directing the flow of liquid and vapors, said sheets being corrugated and arranged in nested relation to each other and slightly spaced apart to form a liquid space of small capacity, and said grids being arranged with the edges of the corrugations of adjacent grids in contact to thereby form paths for the passage of the flue gases.

2. A boiler comprising a plurality of spaced grids each comprising two thin metal sheets united along their edges, said sheets being corrugated vertically and transversely and arranged in nested relation to each other and slightly spaced apart to form a liquid space of small capacity, and said grids being arranged with the edges of the corrugations of adjacent grids in contact to thereby form paths for the passage of flue gases, which paths conduct the flue gases first upwardly, then laterally and then downwardly.

3. A boiler comprising a plurality of spaced grids each comprising thin sheets of metal united along their edges, partition means between the sheets of each grid for directing the flow of liquid and vapors, said grids being corrugated and arranged with the edges of the corrugations in contact to form paths for the passage of flue gases, a header for supplying liquid to the boiler,

and a header for receiving vapors therefrom.

4. A boiler comprising a plurality of spaced grids each comprising two thin sheets of metal united along their edges, said grids as a whole being corrugated so the sheets of each grid are equally spaced apart, and said grids being arranged with the edges of the corrugations in contact to form paths for the 10 passage of the flue gases, said corrugations being disposed vertically and laterally so that a plurality of parallel paths are pro-

vided which conduct the flue gases first vertically upward at the center of the boiler, then laterally in each direction to the sides 15 of the boiler, and then downward along the sides of the boiler.

In witness whereof, LOUIS C. LOEWENSTEIN has set his hand this 21st day of October 1919, and HARVEY N. DAVIS has set his 20 hand this 24th day of October 1919.

LOUIS C. LOEWENSTEIN.
HARVEY N. DAVIS.
